Attorney.

UNITED STATES PATENT OFFICE.

GEORGE E. MARCH, OF MUSKEGON, MICHIGAN.

SCREEN FOR NOZZLES.

Application filed March 30, 1923. Serial No. 628,942.

The present invention relates to screens for nozzles, particularly such as are employed to vent water from the horizontally-disposed water pipes of an irrigating or sprinkling system; and its object is, generally, to provide an improved screen for such a nozzle whereby any solid matter in suspension in the water may be prevented from stopping or interfering with the flow of water through the nozzle; and, more particularly, to provide such a screen formed from a foraminous sheet bent in such manner as to provide a hollow cylindrical screening member having a closed end, and adapted to be holdingly fitted in the nozzle.

This and any other objects hereinafter appearing are attained by, and the invention finds preferable embodiment in, the structure hereinafter particularly described in the body of this specification and illustrated by the accompanying drawings, in which:

Figure 1 is a vertical central longitudinal sectional view of a portion of an irrigating pipe, having nozzles to which my improved screens are applied, one of which is shown in central longitudinal section taken on line 1—1 of Figure 2;

Figure 2 is an under side fragmentary view of the same, one of the nozzles and its screen being shown in transverse section taken on line 2—2 of Figure 1;

Figure 3 is a side view (reduced in size) of said pipe illustrating nozzles having my screens applied thereto;

Figure 4 is a transverse sectional view of the pipe taken on line 4—4 of Figure 3;

Figure 5 is a view of a blank or foraminous sheet from which the screen is formed; and

Figure 6 is a side view of the screen formed by bending said blank or sheet.

In the embodiment of my invention chosen for illustration by the drawings and for detailed description in the body of this specification, a portion of a horizontally disposed pipe 1 through which water for irrigating or sprinkling passes is shown, to which pipe are applied a plurality of nozzles 2, spaced apart at desired intervals. As thus illustrated, these nozzles are threaded into openings through the wall of the pipe. Each nozzle has a passage therethrough, the inner portion 3 of which passage is cross-sec-

tionally larger than the vent or outer portion 4 thereof. A screen 5 hollow-cylindrical in form is seated in the inner portion 3 of said passage through the nozzle and, as shown, extends outwardly beyond the inner end 6 of the nozzle and into the interior of the pipe 1.

These screens are formed from a blank shown in Figure 5, being a foraminous sheet (as of brass or the like) having a substantially-rectangular body portion 7, and adjacent one end of said body portion a plurality of extensions 8 tapering outwardly toward their extremities or points 9; and said blank has preferably also a slightly tapering portion 10 adjacent the blank's opposite end.

This blank is fashioned to form the screen (particularly well shown in Figure 6) by bending into hollow cylindrical form its middle or body portion 7 and bending the extensions 8 toward and into contact with each other to form a hemispherical closed end 11 of the screen; and by bending the slightly tapering portion 10 of the blank into slightly tapering frustro-conical form seen in Figure 6.

The screen thus formed is seated in the enlarged portion 3 of the nozzle's passage by thrusting thereinto the frustro-conical portion 10 of the screen, and is held in such portion of the passage by the wedging contact of the frustro-conical portion of the screen therewith. The end 11 and the hollow cylindrical body or middle portion 7 of the screen extend into the pipe 1, so that the water passing through the nozzle must first pass through the foraminous body portion 7 and closed end 11 of the screen, whereby solid matter in suspension in the water is screened out.

It will be seen that the bent over extensions 8 of the screen, extending as thus bent transversely to the cross-section of the cylindrical portion of the screen, hold said cylindrical portion in its bent shape.

In the particular construction illustrated, the nozzles are shown provided with deflectors 12 to direct the stream issuing from the vents 4 in a desired direction.

I claim:

In a nozzle; a screen consisting of an integral foraminous sheet having a body por-

tion, a slightly tapering end portion and a plurality of outwardly-tapering extensions adjacent its opposite end, the body portion of the sheet being bent into hollow cylindrical form, the tapering end portion being bent into hollow frustro-conical form, and the extensions being bent toward and into

In testimony whereof I have hereunto set my hand at Grand Rapids, Michigan, this 27th day of March, 1923.

GEORGE E. MARCH.
